UNITED STATES PATENT OFFICE.

CHARLES DENNISTON BURNLEY, OF KILMESTON, ALRESFORD, ENGLAND.

HYDROAERONAUTICAL APPARATUS.

1,107,260.

Specification of Letters Patent. Patented Aug. 18, 1914.

Application filed February 17, 1913. Serial No. 748,939.

To all whom it may concern:

Be it known that I, CHARLES DENNISTON BURNLEY, a subject of the King of Great Britain and Ireland, residing at Dean Holme, Kilmeston, Alresford, in the county of Hants, England, have invented new and useful Improvements in or Relating to Hydroaeronautical Apparatus, of which the following is a specification.

This invention relates to improvements in or relating to hydroaeronautical apparatus and has for its object to enhance the stability of such apparatus particularly during certain stages in their transition from the hydrovolant to the aerovolant condition.

In the specification which accompanied my patent application filed on the 14th December, 1912, Ser. No. 736,836, is described a hydroaeronautical machine wherein the fuselage consists of a water-tight boat-like structure, beneath which are arranged hydropeds furnished with numerous hydroplanes; the latter being arranged in "step" formation; that is to say in superposed horizontal planes. It is comparatively easy to provide for the stability of such a machine when lying at rest upon the water or when traveling at a low speed. Wing-warping devices or other stabilizing means may also be brought into operation when the machine has left the water and is launched in flight. Intermediate between these two conditions there are, however, stages during which stability in such apparatus is difficult to preserve, and my present improvements are designed to insure stability during the transition stages above referred to.

In the accompanying drawings, Figure 1 is a side elevation and Fig. 2 a front elevation illustrating the application of my present improvements to, by way of example, a machine of the particular character above referred to. Fig. 3 shows in detail the manner in which certain of the controls are interconnected.

Upon the hydropeds *a* I mount directional rudders *b* which are preferably of the balanced type and whereof the controls are so interconnected to the wing-warping controls as to operate simultaneously and in sympathy therewith. Under such conditions, continuity of control for stabilizing purposes as the apparatus leaves the water is secured.

Assuming the apparatus to be traveling over water with the water rudders *b* im-

mersed, any tendency of the apparatus to list—for example, to starboard—is corrected by so operating the rudders that their thrust exerts a righting couple tending to bring the port side hydroped more directly beneath the body of the machine. A further righting couple is also exerted when the hydropeds *a* are only partially but unequally immersed, owing to the difference in their respective normal thrusts. A similar effect is obtainable by the employment of swiveling propellers. It will also be apparent that a like result may be accomplished by varying the angle of incidence or the area of the hydroplanes. For the purpose in view, these several means may accordingly be regarded as equivalent.

It will be obvious that stabilizing rudders or equivalent means such as above referred to are equally applicable to hydroplanes of other types, such as those wherein the hydroplanes are formed as buoyant floats. According to the present design, the stabilizing rudders *b* are mounted upon inclined axes, the hydropeds being inclined; but it will be apparent that similar stabilizing effects could be secured with the aid of submerged rudders mounted on vertical or horizontal axes.

A vertically arranged tail hydroped *c* is in addition provided and carries a water rudder *d*, whereof the function is mainly directional as also a submerged elevator *e*; each of these elements being so interconnected with the corresponding aerial appliances as to operate simultaneously and in sympathy therewith.

In Fig. 3 is illustrated the manner in which the water stabilizing rudders *b* and the wing-warping appliances, the tail water rudder *d* and the aerial directional rudder, and the water elevator *e* and the aerial tail-elevator are respectively interconnected.

The hand-wheel *f*, rotatably mounted upon the pillar *f'*, is furnished with a drum *f*², about which are wound the cable *g*, serving by means of the levers *g'*, *g'* to operate the wing-warping or like aerial stabilizing appliances, and the cable *h*, serving by means of the levers *h'*, *h'* to control the water stabilizing rudders carried at the lower extremities of the spindles *d'*.

The pillar *f'* may be vibrated in a longitudinal vertical plane; the transverse shaft *l* being pivotally mounted as to its extremities in suitable journals or bearings arranged in

the fuselage. To the levers l' , l' are connected cables m , adapted to actuate the levers m' which control the aerial elevator tips n and to the levers l' , l' are also attached cables o , o , adapted to actuate the levers o' , o' , which serve to raise or depress the rod p . This rod extends downward within the tail hydroped c and serves to raise or depress the rear edge of the water elevator c , the latter being pivoted near its leading edge to the foot of the hydroped c , as illustrated in Fig. 1. In like manner, the cables r and s are connected to a foot lever t and serve respectively to actuate the lever r' controlling the aerial directional rudder v and to vibrate the water rudder d , the latter effect being obtained by rotating the rod p by means of the lever p' and thereby vibrating the water rudder d ; this rudder being mounted, toward the lower extremity of the said rod p in such a manner that the latter can be raised or depressed, without actuating the said rudder d .

I claim:

- 25 1. In a hydro-aeronautical machine, the herein described means for maintaining stability of the apparatus, particularly during periods intermediate between its hydrovolant and aerovolant conditions, such means comprising hydropeds which project outwardly and downwardly on either side of the machine and are furnished with water stabilizing planes mounted to vibrate about inclined axes, substantially as set forth.
- 30 2. In a hydro-aeronautical machine fur-

nished with hydropeds carrying stabilizing planes for use in water and with aerial stabilizing appliances, the combination with the said water stabilizing planes and aerial stabilizing appliances of interconnections 40 adapted for operating both simultaneously and in sympathy, substantially as set forth.

3. For use in a hydro-aeronautical machine, a control lever formed as a lateral extension from a transverse shaft and carrying at its upper extremity a hand-wheel the transverse shaft being moreover provided with two double-arm levers; in combination with an aerial elevator connected to the double-arm levers, an elevator for use in 50 water connected to the same levers, aerial lateral stabilizing appliances connected to the hand-wheel, and stabilizing planes for use in water connected to the same wheel.

4. For use in a hydro-aeronautical machine, the combination, with a two-arm foot-bar pivoted centrally, of an aerial directional rudder mounted upon the tail of the machine and a direction rudder for use in water mounted toward the lower extremity 55 of a dependent hydroped, both the said rudders being connected to each of the arms of the foot-bar, whereby continuity in directional control is obtained while passing from the hydrovolant to the aerovolant condition and vice versa.

CHARLES DENNISTON BURNETT.
